UNITED STATES PATENT OFFICE.

CHARLES D. ROGERS, OF PROVIDENCE, RHODE ISLAND.

DRIVE-SCREW.

SPECIFICATION forming part of Letters Patent No. 364,302, dated June 7, 1887.

Application filed October 13, 1886. Serial No. 216,098. (No model.)

To all whom it may concern:

Be it known that I, CHARLES D. ROGERS, a citizen of the United States, residing at Providence, in the county of Providence and State 5 of Rhode Island, have invented certain new and useful Improvements in Drive Screws or Nails; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention herewith relates to improvements in drivescrews or nails; and it consists of a drive screw or nail having a head, a roughened shank adjacent to the head, a helical groove or thread formed on the body of the wire whose 20 diameter exceeds the normal diameter of the wire stock and terminating in a sharpened and threaded point, all as will be more fully hereafter set forth and claimed.

The object of this invention is to produce a 25 drive-screw having superior holding qualities, said invention being an improvement in the wire nail shown and claimed in my pending application for United States Letters Patent filed August 6, 1886, Serial No. 210,165.

30 Figure 1 in the accompanying sheet of drawings represents a perspective view of my improved drive-screw as provided with a head, a roughened shank, and an enlarged screw-thread terminating in the sharpened or conical screw-threaded point. Fig. 2 is a similar view showing said nail provided with an enlarged ratchet-shaped thread extending to the point of the conical-shaped end, and Fig. 3 represents a perspective view of the drive 35 screw or nail having a series of enlarged annular corrugations formed thereon and extending to the point of the screw.

The following is a more detailed description of the invention:

A in the drawings designates the improved 45 drive-screw as a whole, the same consisting of the shank *s*, nicked head *h n*, roughened portion *r* adjacent to the head, and the screw-threaded portion *t*, terminating in the sharpened or conical-shaped point *p*, the latter also being screw-threaded, the diameter of the said thread *t* being somewhat larger than the wire stock or shank *s*, as clearly shown.

In Fig. 2 the form of the screw-thread is represented as "ratchet-shaped," the same being 55 enlarged as compared with the normal diameter of the shank *s*, and also extending to the extreme end of the conical point *p*.

In Fig. 3 a series of enlarged corrugations *t* is formed on the body or shank of the screw 60 or nail, the same in like manner extending to the end of the sharpened point.

I would not be understood, however, as limiting myself to the particular form of screw-thread shown in the drawings, as various 65 kinds may be used in connection with the roughened shank *r* without departing from the spirit of the invention.

I disclaim as my invention a gimlet-pointed wood-screw having a reduced stem or shank; 70 but

What I do claim, and desire to secure by United States Letters Patent, is—

As a new article of manufacture, the drive-screw hereinbefore described, having a head, 75 a roughened shank adjacent to said head, a screw-thread of greater diameter than the normal size of the wire or shank, and a sharpened screw-threaded point, substantially as shown and set forth.

In testimony whereof I have affixed my signature in presence of two witnesses.

CHARLES D. ROGERS.

Witnesses:

CHARLES HANNIGAN,
GEO. H. REMINGTON.
